US00D618226S

(12) **United States Design Patent**
Tong et al.

(10) **Patent No.:** **US D618,226 S**
(45) **Date of Patent:** **** Jun. 22, 2010**

(54) **CELLPHONE PLUG ADAPTER**

(75) Inventors: **Chi Lun Tong**, Kowloon (HK); **Ka Wah Lai**, Tseung Kwan O (HK)

(73) Assignee: **Telebrands Corp.**, Fairfield, NJ (US)

(**) Term: **14 Years**

(21) Appl. No.: **29/315,651**

(22) Filed: **Jul. 13, 2009**

(51) **LOC (9) Cl.** **14-02**

(52) **U.S. Cl.** **D14/240; D14/431.1; D14/242; D14/356; D13/133**

(58) **Field of Classification Search** **D13/133; D14/133, 240, 484.1, 480.6, 435.1, 358, 374, D14/242, 361-363, 365-367, 433; 361/757; 439/131, 159, 501, 528, 623, 652, 654; 379/220.1, 379/25, 93.09, 93.15, 93.14, 156, 424; 451/550.1, 451/557**

See application file for complete search history.

(57) **CLAIM**

The ornamental design for a cellphone plug adapter, as shown and described.

DESCRIPTION

FIG. 1 is a perspective view of a cellphone plug adapter showing our new design;

FIG. 2 is a front view thereof;

FIG. 3 is a rear view thereof;

FIG. 4 is a side view thereof;

FIG. 5 is the other side view thereof;

FIG. 6 is a bottom view thereof; and,

FIG. 7 is a top view thereof.

The broken lines in FIGS. 1, 2, and 3 are for illustrative purposes and form no part of the claimed design.
